UNITED STATES PATENT OFFICE

RICHARD KASTNER, OF STEYRERMUHL, AUSTRIA

METALLIC CLOTH FOR PAPER-MAKING MACHINES

Application filed September 4, 1928, Serial No. 303,945, and in Austria December 24, 1926.

This invention relates to metallic cloths for paper making machines. In the metallic cloths and metallic fabrics of a known kind with the usual simple interlacing between 5 warp and weft there is point contact between the metallic cloth and the surfaces contacting with it. This point contact leads to high local pressures and causes relatively rapid wear of the metallic cloths. Attempts 10 have been made to reduce the bulging places of the warp by using warps having a flattened cross-section. It has also been proposed to make metallic cloths with a two wire warp. Such metallic cloths, however, 15 have the disadvantage that they mark the papers too strongly.

The present invention has for its object to provide a metallic cloth, the essential feature of which is, that the fabric makes linear contact with the surface in contact with it and which does not have the disadvantage of producing sieve markings in the paper. The metallic cloth according to the invention is characterized by the feature that it is woven 25 with a multiple weft i. e. a double or multiple weft, the two or more wefts being in contact with one another in the weave. Preferably for a metallic cloth such a fabric is used having a plain weave. Other weaves 30 have the disadvantage compared with plain weave that they mark the paper.

In a fabric such as that according to the invention the warp threads or warp wires therefore lie on the surface for a greater distance than in an ordinary weave and the portions of the warp threads or wires lying over and under the weft have a straight axis running parallel to the plane of the cloth or sieve. Such a line contact has this advantage over 40 the usual point contact of the well-known metallic woven or braided fabrics, that local pressures in the wearing surfaces can be considerably reduced, thus saving the material and increasing its life and durability.

45 The same effect as with a double or multiple weft can be obtained with a weft of angular, for instance rectangular, or flat, for instance oval, cross-section.

Hence, for manufacturing a woven fabric 50 according to the invention with round warp

wires a weft is used consisting of a wire of flat or elongated cross-section or of two or more wires of round cross section.

The use of two or more wires as weft has the advantage that with a fabric having the same weight per unit area a thinner metallic fabric or sieve is obtainable than with a single weft, for, if instead for instance of a single wire of diameter d and weight g per meters run two wires of diameter d' be used, 60 each of which per meters run weights only

$$\frac{g}{2},$$

for the same weight a thinner woven fabric is 65 obtained than is the case when a single weft is used and the fabric will be considerably more flexible, which is of great advantage more especially for sieves and metal cloths which as endless bands travel over rollers and 70 the like.

The invention thus also provides means for considerably increasing the flexibility of metallic cloths or metallic fabrics.

The invention is shown diagrammatically 75 in the accompanying drawings in which Fig. 1 shows a cross section taken through a weft wire of a metallic cloth according to the present invention, in which wires of a flattened cross-section are used as the weft and wires 80 with a round cross-section are used as the warp.

Fig. 2 shows an illustration similar to Fig. 1 of another embodiment of the invention.

Figs. 3 and 4 show another embodiment of 85 the invention in which the weft consists of two wires having a round cross section.

Fig. 5 shows an embodiment of the invention similar to Fig. 3 in which at the seam of the metallic cloth weft wires of larger diameter 90 are woven in.

Fig. 6 illustrates diagrammatically the process in the manufacture of the wire cloths.

In the examples shown in Figs. 1 and 2 wires of a flattened cross-section are used as 95 the weft b . The example of Fig. 2 has this advantage over that of Fig. 1, that the warp wires above and below the weft run in a straight line and thus offer a line contact with the surfaces resting on them.

In the example of Figs. 3 and 4 the weft consists of two wires b' , b' . The wires bear the reference letter a' . The portions of the warp wires lying above and below the multiple weft b' , b' have a straight axis parallel to the plane of the sieve.

The constructional form shown in Figs. 3 and 4 has certain advantages where seams have to be made for forming endless bands. 10 As is well known, in making seams for forming endless bands, the two ends of the fabric are placed with corresponding warp wires opposite one another and are sewn together with a sewing wire which is passed helically over the weft wires lying on either side of the joint. In the fabric with double wefts shown in Figs. 3 and 4, owing to the fact that the sewing wire is not itself specially exposed to wear, as has been the case in the constructional forms used hitherto, but is supported by the weft threads which present a broad surface, a substantial strengthening of the seam is attained.

The seam may be further strengthened by 25 the weft wires lying on either side of it being of somewhat larger diameter d over a suitable length or breadth of the fabric, for instance the breadth e of 5 to 10 cm. (Fig. 5), whereby the fabric on either side of the seam 30 forms a pad and the sewing wire h can recede somewhat with respect to the outer surface of the fabric, so that it is protected from becoming worn.

a^1 are the warp wires and b^1 the double 35 wefts.

The manufacture of such a wire cloth is effected by picking one and the same weft b^1 by means of a single shuttle or other device, two or more times in succession into the same 40 shed formed by the warp a^1 . In order, however, that the weft, in its reversal, may not be drawn out of the shed again, one or more warp wires i (the drawing shows three by way of example) are arranged at the lateral 45 edge of the cloth, and the weft b^1 is bound in with the warp wires i before its reversal, these warp wires i changing the shed and the 50 weft b^1 forming with them a selvedge of the breadth k . By arranging such a selvedge only on one side of the sieve cloth, the weft can be picked twice, and by arranging it on 55 both sides it can be picked as often as desired in the same shed of the warp a^1 .

What I claim is:

1. A metallic cloth for paper making machines comprising weft and warp wires, a plurality of weft wires arranged side by side and in contact with each other said weft wires being placed in the sheds formed by the warp wires.
2. A metallic cloth for paper making machines comprising weft and warp wires, the sheds of the warp wires forming elongated recesses, and in which at least two weft wires 65 are placed in contact with each other and

fully occupying the recesses to sustain the sheds of the warp wires in planes parallel to the plane of the cloth.

3. A metallic cloth for paper making machines comprising warp wires, the sheds of the warp wires defining substantially flat recesses, and a plurality of weft wires having intimate contact with each other and occupying the recesses and serving to sustain the sheds of the warp wires in a plane for a major portion of their length in planes parallel to the plane of the cloth.

4. A metallic cloth for paper making machines comprising warp and weft wires, the sheds of the warp wires forming throughout their length elongated recesses, the weft wires being rectangular in cross section for fully occupying said recesses.

In witness whereof I have hereunto signed my name.

RICHARD KASTNER.
